(57) **CLAIM**

The ornamental design for a frusto-conical container with
brush, as shown.

DESCRIPTION

FIG. 1 is a side elevational view of a frusto-conical container
with brush showing our new design;

FIG. 2 is a side elevational view of a second embodiment of
the frusto-conical container with brush;

FIG. 3 is a side elevational view of a third embodiment of
the frusto-conical container with brush; and,

FIG. 4 is a side elevational view of a fourth embodiment of
the frusto-conical container with brush.
